CLAIM

The ornamental design for a truck body, as shown and described.

DESCRIPTION

FIG. 1 is a rear perspective view of a truck body showing our new design;

FIG. 2 is a front perspective view of the truck body of FIG. 1;

FIG. 3 is a side elevation view thereof;

FIG. 4 is a front elevation view thereof;

FIG. 5 is a rear elevation view thereof;

FIG. 6 is a bottom plan view thereof; and,

FIG. 7 is a top plan view thereof.

The broken lines shown in FIGS. 1-7 are for illustrative purposes only and form no part of the claimed design.
